CLAIM

We claim the ornamental design for a safety vest light, as shown and described.

DESCRIPTION

FIG. 1 is a perspective view of the safety vest light shown in an environment of use;

FIG. 2 is a front elevation view of the safety vest light;

FIG. 3 is a top view thereof;

FIG. 4 is a bottom view thereof;

FIG. 5 is a side elevation view thereof;

FIG. 6 is a side elevation view thereof; and,

FIG. 7 is a rear elevation view thereof.

The dash-dash broken lines in FIG. 1 depict environmental subject matter only that forms no part of the claimed design. The broken lines showing the circular pattern on the rear surfaces in FIGS. 3-7 depict surface ornamentation that forms no part of the claimed design. The dot-dash broken lines depict portions of the safety vest light that form no part of the claimed design.

1 Claim, 4 Drawing Sheets
